UNITED STATES PATENT OFFICE.

ALFRED H. PRITCHARD, OF TORONTO, ONTARIO, CANADA.

APPARATUS FOR MAKING SOAP.

No. 910,083.

Specification of Letters Patent.

Patented Jan. 19, 1909.

Application filed January 20, 1908. Serial No. 411,866.

To all whom it may concern:

Be it known that I, ALFRED H. PRITCHARD, of the city of Toronto, in the Province of Ontario, Canada, have invented certain new and useful Improvements in Apparatus for Making Soap, of which the following is a specification.

The object of my invention is to devise soap boiling apparatus which while of great capacity will so thoroughly agitate the soap mixture and circulate it over the heating surfaces of the apparatus that complete saponification is assured.

In brief, my apparatus comprises a vessel of oblong form with rounded ends in which are placed two annular headers of smaller diameter than the width of the vessel, and each provided with a series of steam tubes extending up therefrom. Each header is raised above the bottom to admit of the introduction at the bottom of a rotary scraper connected to a central shaft. To each shaft is connected a lifting screw adapted to cause a circulation of the soap up the central space between the tubes and down outside the tubes. The material at the bottom of the prismatical spaces between the headers and tubes is worked towards the center to bring it within the scope of the scrapers and lifting screws by reciprocating agitators which work from the sides toward the center at the bottom of the vessel.

Figure 1 is a vertical longitudinal section of my improved apparatus. Fig. 2 is a plan view of the same. Fig. 3 is a vertical cross section.

In the drawings like letters of reference indicate corresponding parts in the different figures.

A is a steam jacketed vessel, *a* being the steam inlet, and *b* a drip cock or outlet. This vessel is preferably oblong in plan with semi-circular ends.

B are gate valves communicating with the interior of the vessel, through its double bottom, which serve to empty the vessel.

Above the bottom of the interior of the vessel are located at opposite ends the annular headers D, supported by brackets *d* on the inside of the vessel. Each header is of less diameter than the width of the vessel, and is provided with a steam inlet pipe *e* and with an outlet pipe *f* extending through the side of the vessel, and provided of course with suitable valves. In the drawings the outlet pipe *f* of the left hand header is

shown connected with the inlet pipe *e* of the right hand header so that the steam passes from one header to the other.

Extending up from each header is a series of steam pipes E, each closed at its upper end. Each pipe will preferably be divided by a vertical partition to aid circulation in the pipe, but this is an ordinary device and forms no part of my invention.

Centrally within each header and its ring of steam pipes is suitably journaled a vertical shaft F driven by bevel gearing G from the driving shaft H suitably journaled in bearings connected to the upper part of the vessel. The shaft is preferably provided with a fast, a loose and reversing pulley as shown. Formed on each vertical shaft is a lifting screw or worm I extending from a point near the bottom of the vessel to the upper ends of the pipes E. Secured to the bottom of each shaft is a rotary scraper J, consisting of one or more arms preferably inclined, as shown, so that when rotating in the direction indicated by arrow it will lift the soap mixture from the bottom of the vessel. These arms extend substantially to the inner circumference of the vessel.

It will be noted on reference to Fig. 2 that between the two heating devices, formed by the headers with their vertical pipes, and the sides of the vessel are formed two substantially prismatical spaces substantially triangular in cross section. In these spaces the saponified soap mixture would be liable to accumulate. To avoid this and cause a perfect circulation I provide an agitator located at the bottom of each space. Each agitator comprises a series of slats K secured to a bar L.

These slats are set at an angle to the horizontal, preferably being inclined towards the adjacent side of the vessel. This bar L rests upon a track M, and the slats are notched to pass on each side of this track in order that they may extend close down to the bottom of the vessel. By reciprocating these agitators on the tracks the soap mixture will be lifted from the bottom of the vessel and moved towards the center where it will come within the sphere of action of the scrapers J and the worms I, which produce a constant suction tending to draw material from all sides and force it upward within the spaces inclosed by vertical pipes E. For the purpose of operating these agitators I fulcrum adjacent to each agitator a bell crank lever N. Each bell crank lever is connected by a

pitman O with a crank formed on a crank shaft P suitably journaled on the vessel at right angles to the shaft H. Each of these crank shafts is directly driven by a bevel gear wheel Q from a bevel gear wheel R fast on the shaft H.

The operation of my device is substantially as follows;—When the vessel is full of the soap mixture the rotation of the lifting 10 screws or worms I draws it up through the passageways formed by the annular headers and their rows of connected pipes and discharges it out into the space between the pipes and the inner walls of the vessel. The 15 soap mixture passes down this space to the bottom where it is cut by the rotary scrapers J and the agitators, and is assisted to move into the center to be again lifted by the screws I. Thus a constant and thorough 20 agitation of the soap mixture is obtained, and it is constantly circulated over the heated surfaces of the apparatus. I am thus enabled to secure a complete saponification and am enabled to produce as large a quantity 25 of soap from a given quantity of material as can possibly be obtained, and in a comparatively short space of time.

What I claim as my invention is:—

1. In soap making apparatus the combination of an oblong vessel, two externally substantially cylindrical heating devices suspended in said vessel side by side above the bottom, and providing vertical internal passages for soap material; means for elevating 30 soap material through said passages; and agitators in the spaces between the heating devices adapted to move soap material towards the heating devices.

2. In soap making apparatus the combination of an oblong vessel, two externally substantially cylindrical heating devices suspended in said vessel side by side above the bottom, and providing vertical internal passages for soap material; means for elevating 40 soap material through said passages; and agitators located at the bottom of the vessel in the spaces between the heating devices and movable to and from the sides of the vessel.

3. In soap making apparatus the combination of an oblong vessel, two externally substantially cylindrical heating devices suspended in said vessel side by side above the bottom, and providing vertical internal 50 passages for soap material; means for elevating soap material through said passages; and agitators comprising a series of longitudinal

parallel slats suitably connected together at an angle to the horizontal, located at the bottom of the vessel in the spaces between the heating devices, and movable to and from the sides of the vessel.

4. In soap making apparatus the combination of an oblong vessel with rounded ends; two annular headers of less diameter than the width of the vessel and located within the latter above the bottom; steam connections for the headers; steam heating pipes extending up from the headers; a vertical shaft suitably carried centrally of each 60 header; a rotary scraper connected to each shaft at the bottom of the inside of the vessel; a lifting screw on each of said shafts; and agitators in the spaces between the heating devices adapted to move soap material 70 towards the heating devices.

5. In soap making apparatus the combination of an oblong vessel with rounded ends; two annular headers of less diameter than the width of the vessel and located within the latter above the bottom; steam connections for the headers; steam heating pipes extending up from the headers; a vertical shaft suitably carried centrally of each 80 header; a rotary scraper connected to each shaft at the bottom of the inside of the vessel; a lifting screw on each of said shafts; and agitators located at the bottom of the vessel in the spaces between the heating devices, and movable to and from the sides of 90 the vessel.

6. In soap making apparatus the combination of an oblong vessel with rounded ends; two annular headers of less diameter than the width of the vessel and located within the latter above the bottom; steam connections for the headers; steam heating pipes extending up from the headers; a vertical shaft suitably carried centrally of each 95 header; a rotary scraper connected to each shaft at the bottom of the inside of the vessel; a lifting screw on each of said shafts; and agitators comprising a series of longitudinal parallel slats suitably connected together at an angle to the horizontal, located 100 at the bottom of the vessel in the spaces between the heating devices, and movable to and from the sides of the vessel.

Toronto, Ont., 9th December, 1907.

ALFRED H. PRITCHARD.
